Primary Examiner — John Windmuller(74) *Attorney, Agent, or Firm* — Clause Eight IPS; Michael Catania(57) **CLAIM**

The ornamental design for an antenna, as shown and described.

DESCRIPTION

FIG. 1 is a top plan view of an antenna with broken lines showing a cover.

FIG. 2 is a side plan view of the antenna of FIG. 1.

FIG. 3 is a top perspective view of the antenna of FIG. 1.

FIG. 4 is a bottom plan view of the antenna of FIG. 1.

FIG. 5 is a side view of the antenna of FIG. 1; and,

FIG. 6 is a bottom perspective view of the antenna of FIG. 1.

The broken line showing is for illustrative purposes only and

forms no part of the claimed design.
